UNITED STATES PATENT OFFICE.

CURTIS HUSSEY VEEDER, OF HARTFORD, CONNECTICUT, ASSIGNOR TO THE VEEDER MANUFACTURING COMPANY, OF HARTFORD, CONNECTICUT, A CORPORATION OF CONNECTICUT.

DUPLEX COUNTING MACHINE.

Application filed February 24, 1923. Serial No. 620,878.

To all whom it may concern:

Be it known that I, CURTIS HUSSEY VEEDER, a citizen of the United States, residing in Hartford, in the State of Connecticut, have invented certain new and useful Improvements in Duplex Counting Machines, of which the following is a specification, reference being had to the accompanying drawings, forming a part hereof.

In the application of counting machines to other machines for the purpose of registering the number of operations of the main machine, such as a loom, for example, it is sometimes desirable to provide two counting mechanisms either one of which can be put into operative relation with the moving part of the main machine so that the number of operations during a given period of time, can be registered independently of the number of operations during another given period of time, as, for example, the number of operations or picks of a loom during the day shift and the number of picks of the same loom during the night shift. The object of this invention is to provide a duplex counting machine of the general class referred to, with improved devices whereby either counting mechanism at will can be connected operatively with the moving part of the main machine. Incidentally provision is made for maintaining in proper working condition the working parts of a numbering machine which, as in the particular use suggested, is subjected to constant vibration and wear. The invention will be more fully explained hereinafter with reference to the accompanying drawings in which it is illustrated and in which—

Figure 1 is a view in elevation of the improved duplex numbering machine.

Figure 2 is a view of the same in section on the plane indicated by the broken line 2—2 of Figure 1.

Figure 3 is a view of the same in elevation as seen from the right hand in Figure 1.

Figure 4 is a view in section on the plane indicated by the broken line 4—4 of Figure 1.

The working parts of the improved duplex counter are received within and supported by a suitable casing a , the front plate a' of which is provided with two

sight openings a^2 through which the two sets of number wheels b may be read. Two numbering machines may be constructed and arranged to operate in any usual or suitable manner, except for the provision of the separating plates c . In the operation of looms the loom counters are often subjected to very severe vibration which has been found to occasion side wear of the number wheels to such an extent that lost motion sometimes becomes excessive and the transmitting gears and pinions cease to function properly and become tied up. For the purpose of overcoming this difficulty the separating plates c , shown in Figure 2 are placed between the several number wheels b and the corresponding transmitting pinions b' . They are fitted into the notched edges of the frame work b^2 which supports the number wheels and the transmitting devices, at both the top and the bottom, and are therefore placed accurately and held securely.

Each of the counting machines is provided as usual with a gear d by which the machine is driven and in the improved machine the two gears d are adapted to be engaged, the one or the other, by a common driving pinion e , which is shiftable into engagement with one or the other of the gears d as may be required. As shown, the common driving pinion e is mounted on a spindle e' which is supported in a swinging yoke f carried by a spindle f' . A locking yoke g , pivoted at g' co-operates with the spindle e' to hold the pinion e in working relation with one gear d or the other. The pinion e is in constant engagement with a driving worm h on a shaft h' which carries a worm h^2 , in engagement with a worm h^3 on a shaft h^4 , the latter being coupled, as at h^5 to the moving part of the loom or main machine the operations of which are to be registered on the counting machines. The spindle f' , which carries the yoke f , has secured thereto, outside of the casing a , an arm f^2 which may be provided with a locking detent f^3 for co-operation with a locking plate f^4 . A spring detent g^2 co-operates with the driving gear d to lock the train of number wheels against movement by vibrations. The spindle f' is at right angles to the worm h and in close proximity thereto at one side, while

the pinion is at the other side of the worm so that it is oscillated through the small arc necessary to effect engagement with one or the other of the two gears d without disengagement from the worm.

- In the operation of the improved duplex counter it will be understood that the shaft h' is driven continuously from the moving part of the machine, the operations of which 10 are to be registered on the counting machine and that the driving pinion e is therefore driven continuously from the worm h . If the pinion e is in engagement with one 15 of the wheels d , as the upper, as shown in Figure 4, and it should be desired, as at the end of the day shift, to change the operating connection to the other or upper counting machine, the lever f^2 is manipulated and the driving pinion e is shifted 20 thereby from engagement with the upper driving gear d to the lower driving gear d . The pinion will be held in operative engagement with one gear or the other by the locking member g .

I claim as my invention:

1. A duplex counter comprising two counting machines mounted on parallel axes, each having a driving gear, a common shiftable driving pinion for engagement with one gear or the other, a driving worm, 30 a swinging yoke mounted at one side of the worm and supporting the pinion at the other side of the worm in constant engagement therewith, and means to operate the yoke to shift the driving pinion into engagement with one gear or the other.

2. In a counting machine, the combination of a series of number wheels, a series of transmission mechanisms including each a transmitting pinion external to the 40 number wheels, and a series of separating plates co-operating with the number wheels and the transmitting pinions to prevent relative lateral movement thereof.

This specification signed this 20th day of 45 February A. D. 1923.

CURTIS HUSSEY VEEDER.
